UNITED STATES PATENT OFFICE.

REUBEN STANLEY SMITH, OF MILWAUKEE, WISCONSIN, ASSIGNOR TO A. O. SMITH COMPANY, OF MILWAUKEE, WISCONSIN, A CORPORATION OF WISCONSIN.

CONTROLLING MECHANISM FOR INTERNAL-COMBUSTION ENGINES.

1,188,501.

Specification of Letters Patent. Patented June 27, 1916.

Continuation of application Serial No. 857,692, filed August 20, 1914. This application filed May 27, 1915. Serial No. 30,768.

To all whom it may concern:

Be it known that I, REUBEN STANLEY SMITH, a citizen of the United States, residing at Milwaukee, in the county of Milwaukee and State of Wisconsin, have invented a certain new and useful Improvement in Controlling Mechanism for Internal-Combustion Engines, (Case 8,) of which the following is a full, clear, concise, and 10 exact description, reference being had to the accompanying drawings, forming a part of this specification.

My invention relates to controlling mechanism for internal combustion engines, and 15 has for its object the provision of means whereby simple and effective controlling means may be employed in connection with the engine so as to easily control the operation thereof.

20 This is a continuation of my co-pending application, Serial No. 857,692, filed August 20, 1914, one of the modifications incorporating an improvement thereon.

Generally, the device of my invention consists in a lever attached to the exhaust valve 25 of an internal combustion engine. Secured to this lever is a controlling means, preferably in the form of a wire or flexible member which extends to a position where the operator may easily manipulate the same. Also secured to this wire is the throttle of the carburetor so that by operating the wire the throttle of the carburetor may be opened or closed as desired. The throttle and the 30 exhaust valve are so connected that operation of the controlling wire in one direction causes the throttle valve of the carburetor to completely, or almost completely close, before the exhaust valve is operated; a continued operation of the wire in the same direction lifting the exhaust valve from its seat thereby preventing compression within the combustion chamber of the internal combustion engine. When the controlling wire 35 is moved in the opposite direction the exhaust valve will be first seated and then the throttle valve opened to provide a free passage way from the carburetor to the intake manifold of the engine. By means of the 40 device of my invention I am enabled to control both the throttle valve of the carburetor and the exhaust valve by virtue of one controlling means.

My invention will be more clearly understood by referring to the accompanying drawings in which,

Figure 1 is a view partly in elevation and partly in section of a portion of an internal combustion engine provided with the controlling means of my invention; and Fig. 2 is a view similar to Fig. 1 of a slightly modified form of controlling means.

In Fig. 1, 3 illustrates the cylinder of the internal combustion engine provided with an exhaust port 4 and an exhaust valve 5 seated in the walls of the exhaust port. The exhaust valve 5 is provided with a downwardly extending rod 6 terminating in a collar 7 rigidly fixed to the rod. Fitting against a downwardly extending boss 7' of the engine cylinder 3 is a forked spacer 8 provided with prongs 9 between which and the collar 7 is interposed a spring 10. This spring 10 serves to normally hold the exhaust valve 5 in its down, or closed, position. Movable mounted in the crank case of the engine, illustrated at 11, is a plunger 12 arranged when operated to engage the lower end of the rod 6 to lift the rod, and, therefore, the exhaust valve 5, from its seat 15 to provide a passage way from the combustion chamber of the engine to the exhaust manifold. The plunger 12, as is well known in the art, is connected with the crank shaft of the engine and is timed so as to cause the exhaust valve 5 to open at the desired time. Bolted, or otherwise secured, to the top of the cylinder 3 is a casing or manifold 13. The manifold is provided with the usual passage way 14 extending to the supply chamber of a carburetor. The casing 13 is also provided with a tubular chamber 15 extending at right angles to the chamber 14. Arranged to operate within this chamber 15 is a throttle valve 16 in the form of a cup having its base rigidly fixed to the controlling wire, 17. This wire 17 extends upwardly from the throttle valve through a cap 18 screw threaded in the carburetor, as illustrated. If desired a flexible 20 guard 19 may be used surrounding the wire 17 from the carburetor to the operator. The throttle valve 16 in the drawing is illustrated in its open position so that a free passage of the fuel is permitted from the 25 supply reservoir to the engine. To nor-

mally retain the throttle valve in its open position, I provide a spring 20 interposed between the cover 18 and the throttle valve.

The controlling wire 17 extends downwardly through an arm 21 carried by a bifurcated lever 22. The lever 22 is pivoted at 23 to some portion of the internal combustion engine casing, illustrated at 24. The lever, as illustrated, extends outwardly and has its bifurcated end embracing the rod 6 of the exhaust valve 5, its upper face engaging with the lower face of the collar 7. The controlling wire 17 extends downwardly a certain distance below the lower face of the lever 22 and carries an enlarged portion 25.

From the description thus far given, it will readily be seen that the throttle valve 16 may be operated without in any way interfering with the exhaust valve mechanism. If it is desired to raise the exhaust valve 5 from its seat so as to relieve the engine of compression, as, for instance, when it is desired to start the engine, the controlling wire 17 is pulled upwardly by the operator thus moving the throttle valve 16 to its closed position. When the throttle valve has reached its closed position, or nearly so, the enlarged portion 25, carried by the lower end of the controlling wire, engages the lower face of the bifurcated lever 22. As the upward movement of the controlling wire is then continued the portion 25 will cause the lever 22 to be moved to the position indicated in dotted lines, therefore moving the exhaust valve 5 upwardly and off its seat against the tension of the spring 10. The crank shaft of the engine may now be revolved comparatively easily until a certain speed is obtained when the wire 17 is released or moved downwardly to cause the exhaust valve to again assume its seated position. The throttle valve 16 may then be operated in the usual way to control the operation of the engine.

In the slightly modified form illustrated in Fig. 2, the exhaust valve is illustrated at 5^a, its coöperating rod at 6^a, the plunger mechanism at 12^a, and the crank casing at 11^a. The bifurcated lever is illustrated at 22^a and is pivoted at 26 to a projection 27 carried by the stud 28 disposed around the cam operated plunger 12^a. The bifurcated lever 22^a extends inwardly, as illustrated, and is arranged to engage a nut 28' carried by the plunger mechanism. The outer end of the lever 22^a is attached to the controlling wire 17^a extending downwardly to be controlled by the operator. The outer end of the lever 22^a is also connected by means of a connecting piece 29 to a rod 30 which is in turn connected to the throttle valve 31 in the intake manifold 32. The manifold is bolted, or otherwise secured, to the engine casing and is provided with a port register-

ing with the intake port 33 of the engine. The throttle valve 31 is arranged to reciprocate in a circular chamber 34 of the manifold, a passage way being employed between the fuel chamber of the carburetor and the chamber 34. This passage way is not illustrated in the drawings for the reason that it has been broken away in order to more clearly reveal the devices associated with the throttle valve. The throttle valve 31, as illustrated, is rigidly secured to the rod 30 which extends upwardly and carries at its upper end an enlarged portion 35 between which and a cup 36 is disposed a spring 37. This spring 37 serves to normally hold the rod 30, and thus the throttle valve 31, in its up, or open, position. The throttle valve 31, illustrated in the drawings, is shown in its closed position, the controlling wire 17^a having been pulled a certain distance to cause the throttle valve to assume this position. If now, a continued pull is placed on the controlling wire 17^a the bifurcated lever 22^a will be rotated in a clockwise direction, thereby causing its inner, or bifurcated, end to engage with the nut 28 carried by the plunger mechanism 12^a. As this bifurcated end engages the nut and raises it the plunger mechanism will engage the rod 6^a of the exhaust valve 5^a, and thus raise it or remove it from its seat thus providing a passage way between the combustion chamber and the exhaust manifold of the engine.

Having thus described my invention what I claim as new and desire to secure by Letters Patent of the United States is:

1. A device of the class described, comprising an internal combustion engine, a throttle for controlling the supply of combustible fluid to the engine, an exhaust valve for said engine, means for normally retaining the throttle in open position, a wire extending from the throttle arranged when operated to close the throttle, and means interposed between the throttle and exhaust valves whereby the latter is opened when the throttle valve is moved to closed position.

2. A device of the class described, comprising an internal combustion engine, a throttle for controlling the supply of combustible fluid to the engine, an exhaust valve for said engine, means for normally retaining the throttle in open position, a wire extending from the throttle arranged when operated to close the throttle, and means interposed between the throttle and exhaust valves whereby the latter is opened when the throttle valve is moved to closed position, said last-mentioned means having lost-motion connection with the exhaust valve.

3. A device of the class described, comprising an internal combustion engine, a throttle valve for controlling the supply of combustible fluid to the engine, an exhaust valve for said engine, manually-controlled

- devices for operating the throttle valve, and means arranged to open the exhaust valve when the throttle valve is moved to closed position.
- 5 4. A device of the class described, comprising an internal combustion engine, a piston valve controlling the supply of combustible material to the engine cylinder, a spring normally tending to hold the piston valve in open position, an exhaust valve for said cylinder, engine-operated devices for cyclicly operating said exhaust valve, means for manually-operating the piston valve, and means connecting the piston valve and exhaust valve whereby the latter is moved to open position when the piston valve is moved to closed position.
- 10 5. A device of the class described, comprising an internal combustion engine, a throttle controlling the supply of combustible fluid to the engine cylinder, an exhaust valve for said cylinder, means for manually operating the throttle valve, and a lost-motion connection between the throttle valve and exhaust valve whereby the latter is moved to open position when the throttle valve is moved to its fully closed position.
- 15 In witness whereof, I hereunto subscribe my name this 17 day of April, A. D. 1915.

R. STANLEY SMITH.
